United States Patent

Des. 238,101

Patented Dec. 16, 1975

238,101

COMBINED LABEL PRINTER AND APPLICATOR

Robert P. Mulholland, Centerville, Ohio, assignor to Monarch Marking Systems, Inc., Dayton, Ohio

Filed June 5, 1974, Ser. No. 476,485

Term of patent 14 years

Int. Cl. D18—02

U.S. Cl. D64—10

FIG-1

FIG-6

FIG. 1 is an elevational view of a combined label printer and applicator showing my new design;

FIG. 2 is an elevational view of the opposite side thereof;

FIG. 3 is a rear elevational view looking toward the left in FIG. 1;

FIG. 4 is a front elevational view looking toward the right in FIG. 1;

FIG. 5 is a top plan view of FIG. 1; and

FIG. 6 is a bottom plan view thereof.

I claim:

The ornamental design for a combined label printer and applicator, substantially as shown.
